(57) **CLAIM**

The ornamental design for a case for tape cleaner, as shown and described.

DESCRIPTION

FIG. 1 is a perspective view of a case for tape cleaner showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The broken lines showing of a side cover of the case for tape cleaner in FIGS. 2 through 7 are for the purpose of illustrating environmental structure and form no part of the claimed design.
